UNITED STATES PATENT OFFICE

157,769

COMB

Lana Madlock, Los Angeles, Calif.

Application May 11, 1948, Serial No. 146,276

Term of patent 7 years

(Cl. D86—8)

To all whom it may concern:

Be it known that I, Lana Madlock, a citizen of the United States, residing at Los Angeles, in the county of Los Angeles and State of California, have invented a new, original, and ornamental Design for a Comb, of which the following is a specification, reference being had to the accompanying drawing, forming part thereof.

I claim:

The ornamental design for a comb, as shown.
LANA MADLOCK.
